UNITED STATES PATENT OFFICE.

HERBERT B. ALLEN, OF SAN FRANCISCO, CALIFORNIA, ASSIGNOR TO JOHN D. SPRECKELS, OF SAN FRANCISCO, CALIFORNIA.

PRINTING-PRESS.

SPECIFICATION forming part of Letters Patent No. 706,709, dated August 12, 1902.

Application filed February 13, 1902. Serial No. 93,814. (No model.)

To all whom it may concern:

Be it known that I, HERBERT B. ALLEN, a citizen of the United States, residing in the city and county of San Francisco, State of California, have invented an Improvement 5 in Printing-Presses; and I hereby declare the following to be a full, clear, and exact description of the same.

My invention relates to improvements in 10 printing-presses; and it consists, in combination with what is known as "a quadruple perfecting-press," of mechanism whereby a web of paper not exceeding half the width of the press is taken from the rolls and passed 15 through one side of the press and over the printing-rollers therein, is returned over to the starting-point and again passed through and over the printing-rollers within the other half of the press for the purpose of applying 20 a second color or impression, and is thence transmitted to the second portion of the press and in like manner carried through and over printing-rollers by which a third color or impression is applied to the sheet before it passes 25 to the folders and eventually leaves the apparatus.

My invention also comprises details of construction, which will be more fully explained by reference to the accompanying drawings, 30 in which—

Figure 1 is a perspective view showing my attachment. Fig. 2 is a plan view showing the general arrangement of the device. Fig. 3 is a diagrammatic view showing in general 35 the rear part of the press B. Fig. 4 is a rear view of Fig. 3.

The object of my invention is to so construct the press attachments that the paper taken from the roll may be passed over impression-rolls bearing different colors, whereby the paper may be imprinted with a plurality of colors during its passage through the press to the point where it is delivered.

I have here illustrated my invention as applied to what is known as the "Hoe Quadruple Newspaper Perfecting-Press," which consists practically of two separate presses A and B, set at right angles to each other and each provided with printing-rollers over 50 which the paper taken from an endless roll or web is carried and imprinted upon both

sides before being delivered from the press. In my invention I have combined with these structures devices which enable me to return the paper and pass it again over the printing-rolls, each added passage applying a new color or tint. 55

The part A is provided with a holder or support 2 for the web of paper, upon which the roll of paper 3 is mounted and from which it is carried through the press and over the type carrying or printing rollers, as at 4, where one or more colors may be applied to the sheet. The printing-roller has a co-operating inking-roller 4'. The roll or web 3 does not exceed half the full length of the roll-carrier, and after the paper has passed over the printing-rolls which are in the line of its travel it passes over direction-rollers, which take it up to a point above the top of the part A, and from the upper roller 5 it passes horizontally over a diagonally-placed lead roll or bar 6, which is suitably fixed in the line of travel of the paper and so as to change its direction to one at right angles. The web passes in this direction a short distance to a second diagonally-placed lead-bar 7, which directs the web of paper back over the top of the press, as shown at 8. Thence it passes over a direction bar or roller 9, thence over a direction bar or roller 10, thence beneath the direction roller or bar 11, which again passes it through the press and over the color-surfaces of that side of the press and parallel with the web as it first enters the press. These ends of the printing-rollers over which it now passes are supplied with any other color desired, which is thus applied to the paper on its second passage through this part of the press. In order to provide for this return of the paper, I have shown standards 12 fixed upon the main frame of the press and carrying brackets 13, in which the ends of the guide bar or roller 9 are supported at a sufficient distance away from the press to cause the paper to travel clear of it on its return movement to the lower portion. The guide bar or roller 10 in like manner is carried in brackets 14, which are fixed to and projecting from the frame A of the press, and the paper is thus brought to a point where it can be again passed into the press over the guide-roller 11. 95 100

After having passed the second time through the press the paper is again carried up to a point above the top of the portion B of the apparatus by suitable guide-rollers and is carried across the open space between the parts A and B, passing over the lead-bar 7 and thence over a lead-bar 15, which is fixed diagonally across the upper part of B. From this lead-bar the paper passes to the back of the part B, thence over a guide, as at 16, which directs it downwardly, thence over suitable guides, which direct it into the press B, where it passes over other printing-rollers in the line of its travel, whereby a third color may be applied in addition to those that have already been received in the part A.

This device is especially designed for use upon newspapers which have supplemental sheets printed and upon which it is desirable to print in a number of colors. The portion passed through the press, as just described, provides for this color-printing and enables the operator to apply at least three colors.

The portion of the paper which is to be printed in black may be taken from a roll carried upon a guide or roller over which the sheet heretofore described passes from the direction-roller 16 and at the opposite end of the roller, so that it passes through the press simultaneously and parallel with the colored portion in its final passage through the part B.

In Fig. 3 I have outlined the rear portion of the press B to show the direction of the roll of paper after it leaves the direction-bar 16 and passes down over the rear of the press. Thence the paper passes over a roller *a*, thence over another roller *b*, and thence over a series of rollers at *c*. The roll of paper at *d* passes up over direction-rollers *e*, thence over the printing-cylinder *f*, thence over a diagonal direction-bar *g*, and from this bar the paper comes parallel with the other sheet, as shown

at *h*, and the two sheets go into the cutting and folding apparatus (not shown) and are folded together and delivered from the press 45 in any well-known manner.

Having thus described my invention, what I claim, and desire to secure by Letters Patent, is—

1. The combination in a printing-press of 50 the independent presses A and B, a feed-roll from which a continuous sheet is first delivered through one-half of the portion A, diagonally-disposed guides located between A and B over which the paper is passed and by 55 which it is returned over the top of A, direction-rolls whereby the continuous web or sheet is returned parallel with the first portion and again passed through the press, other direction-rollers by which it is carried from 60 the part A over the top of the part B, a diagonal lead-bar over which it passes and by which it is directed over the top of the part B, direction-rollers by which the sheet is transmitted downwardly and into the press B 65 to pass over printing-rollers within said portion.

2. The combination with a two-part press A and B, of diagonally-disposed lead-bars, means by which they are supported between 70 the parts A and B, said bars serving to return a continuous sheet of paper over the top and again into the part A after it has once passed through said part, direction-rollers and a lead-bar located above the part B whereby 75 the continuous sheet finally delivered from A is caused to pass through the portion B to receive a third impression.

In witness whereof I have hereunto set my hand.

HERBERT B. ALLEN.
